CLAIM

The ornamental design for a flashlight, as shown and described.

DESCRIPTION

FIG. 1 is a front perspective view of the design;

FIG. 2 is a rear perspective view of the design;

FIG. 3 is a side view of the design;

FIG. 4 is a side view of the design;

FIG. 5 is a front view of the design;

FIG. 6 is a rear view of the design;

FIG. 7 is a top view of the design; and,

FIG. 8 is a bottom view of the design.

The broken lines shown represent unclaimed portions of the article and form no part of the claimed design.

1 Claim, 6 Drawing Sheets(56)
